(57) **CLAIM**

We claim, the ornamental design for a luminaire, as shown and described.

DESCRIPTION

FIG. 1 is a front view of an exemplary embodiment of the invention, the luminaire being symmetric about a center axis; FIG. 2 is a top view of the exemplary embodiment of FIG. 1; FIG. 3 is a bottom view of the exemplary embodiment of FIG. 1;

FIG. 4 is a top perspective view of the exemplary embodiment of FIG. 1; and,

FIG. 5 is a bottom perspective view of the exemplary embodiment of FIG. 1.

The phantom lines shown in FIG. 1-FIG. 5 are environmental and not part of the claimed design.

The color of the luminaire forms no part of the claimed design; a luminaire according to the claimed design may be of any color or combination of colors.

The shading and tones, and any variations thereof, shown in the figures do not imply any specific colors or color contrast scheme in the claimed design.

The surface treatment of the luminaire shown in the figures forms no part of the claimed design, a luminaire according to the claimed design may have any surface treatment.

References to “front”, “rear”, “side”, “top”, and “bottom” in the figure descriptions are not meant to require certain in-use orientation; a luminaire according to the claimed design may be used in any orientation.
